UNITED STATES PATENT OFFICE

FREDERICK B. RANNEY, OF GREENVILLE, MICHIGAN, ASSIGNOR TO RANNEY REFRIGERATOR COMPANY, OF GREENVILLE, MICHIGAN

ICE RACK FOR REFRIGERATORS

Application filed September 24, 1930. Serial No. 484,160.

This invention relates to an ice rack for ice refrigerators, the general object of the invention being to provide a self-contained unit which is adapted to be placed in the ice chamber of a refrigerator and having supporting means at its top for a block of ice and supporting means below the first supporting means and above the bottom of the unit for chipped ice, the space between the chipped ice and the block of ice forming a chamber into which the air passing downwardly between the block of ice and the walls of the ice chamber will enter, so that the air is further chilled by the cracked ice, after which the air passes around the cracked ice into the food chamber or chambers of the refrigerator. Thus the air is thoroughly chilled before reaching the food chamber or chambers, as it must first pass around the block of ice, then into the space between the block of ice and the cracked ice and then around the cracked ice into the food compartments.

Another object of the invention is to provide hinged members at the sides and rear of the device which act as guiding means for the block of ice being placed on the device so that such members will act to center the block and thus leave air spaces between the block and the walls of the ice chamber. By hinging the members, the device can be readily placed in the ice chamber and removed therefrom. By providing the lower supporting means, the remains of the block of ice on the upper part of the device can be readily broken into chips by the iceman and dropped to the lower compartment, after which the new block is placed on the device and the chipped ice is readily accessible through the door of the ice chamber.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a fragmentary front view, with parts in section, of a refrigerator, showing the invention in use.

Figure 2 is a side view of the unit.

Figure 3 is a section on line 3-3 of Figure 1.

Figure 4 is a perspective view of the unit.

In these drawings, the letter A indicates a pair of end members, each composed of a metal frame having a straight top, downwardly convergent sides and its bottom bent to form the feet 1. Flat bars 2 are fastened to the outer faces of the sides of the two members and extend across the rear member so as to provide an openwork frame and the top portions of the two members are connected together by the flat bars 3. A flat bar 4 is placed on the top of each member A, under the ends of the bars 3, and other bars 5 are fastened to the top faces of said bars 3 and have their rear ends extending beyond the ends of the bars 3. These extended ends are rolled to form the hinge barrels 6 and the ends of the bars 4 are rolled to form the hinge barrels 7. A pair of side grid frames 8 is hingedly connected with the bars 4 by their barrel portions 7 and a rear grid frame 9 is connected with the rear ends of the bars 5 by the barrels 6 so that the grid frames can be folded one upon another on the top of the device or can be raised to a position where their upper edges will rest against the walls of an ice chamber of a refrigerator, as shown in Figure 1.

A flat bar 10 rests upon the bottom piece of each of the members A and extends over the legs 1 and has its ends bent to rest against the side pieces of each member A to which the bent portions are riveted or otherwise fastened, as shown at 11. A corrugated plate 12 rests upon these bars 10 and forms a bottom member which is located above the legs 1. A bottom plate 13 is placed under the corrugated plate and is fastened to the bottom pieces of the members A between the legs 1 of said bottom piece. The device is placed in the ice chamber of a refrigerator, as shown in Figure 1, and as the top part of the device is wider than the door opening, in order to place the device in the chamber through the

door opening, the grid plates 8 and 9 must be folded downwardly and then the entire device is tilted so that it can pass through the door opening. The device is then placed in 5 upright position, with its legs resting upon the bottom of the ice chamber and the device is held in this position by the front upper corners of the device engaging the door frame. The grid plates are swung upwardly until 10 their upper edges rest against the walls of the ice chamber, as shown in Figure 1. The block of ice is then placed in the chamber and upon the top part of the device and in the placing of the block in position, the grid plates act as 15 guiding means for centering the block so that spaces will be left between the block and the sides of the ice chamber for the circulation of the air. Chipped ice is placed on the plate 12 and the residue of the block previously 20 placed in the ice chamber can be broken up by the iceman to produce this chipped ice, as it will only be necessary for the iceman to break up the remains of the block and the pieces will drop on to the plate 12. The new 25 block is then placed in position, as before described.

It will be seen that the air entering the top of the ice chamber will pass downwardly around the block of ice and thus be initially 30 cooled and then the air will pass into the space above the chipped ice and will flow around and through the chipped ice before reaching the food compartment or compartments. Thus the air initially cooled by the 35 block of ice will be super-chilled by entering the space between the chipped ice and the block of ice and by its passage around and through the chipped ice. Thus the air is chilled to the maximum extent without excessive 40 melting of the ice. When it is desired to use the chipped ice, it is simply necessary to open the door of the ice chamber and remove the desired amount of chipped ice from the device and this can be done without touching 45 the block of ice. This invention affords easy disposal of left-over ice, provides a supply of chipped ice and gives the maximum cooling effect without increasing the ice consumption.

50 The device can be easily and quickly removed for cleaning or repair purposes, as it is simply necessary to drop the grid plates and then turn the device so that it can be pulled through the door opening.

55 It is thought from the foregoing description that the advantages and novel features of the invention will be readily apparent.

It is to be understood that changes may be 60 made in the construction and in the combination and arrangement of the several parts, provided that such changes fall within the scope of the appended claims.

What I claim is:—

1. An ice rack for a refrigerator, comprising an openwork frame adapted to be placed

in the ice chamber of a refrigerator, the top part of the frame supporting a block of ice and a plate extending across an intermediate portion of the frame for receiving chipped ice. 70

2. An ice rack for a refrigerator, comprising an openwork frame adapted to be placed in the ice chamber of a refrigerator, the top part of the frame supporting a block of ice, a plate extending across an intermediate portion of the frame for receiving chipped ice and grid plates connected with the top of the frame and resting against the walls of the ice chamber for spacing the block of ice from said walls. 75

3. An ice rack for a refrigerator, comprising an openwork frame adapted to be placed in the ice chamber of a refrigerator, the top part of the frame supporting a block of ice, a plate extending across an intermediate portion of the frame for receiving chipped ice and grid plates hingedly connected with the top of the frame and resting against the walls of the ice chamber for spacing the block of ice from said walls. 80

4. An ice rack comprising an openwork frame having feet forming portions at its bottom and spaced bars extending across its top for supporting a block of ice, a corrugated plate in the frame above the legs thereof and below the top for supporting chipped ice and grid members hingedly connected with the sides and rear of the top of the frame for spacing the block of ice from the side walls of an ice chamber. 90

5. An ice rack comprising an openwork frame having feet forming portions at its bottom and spaced bars extending across its top for supporting a block of ice, a corrugated plate in the frame above the legs thereof and below the top for supporting chipped ice and grid members hingedly connected with the sides and rear of the top of the frame for spacing the block of ice from the side walls of an ice chamber, the front of the frame being open to provide access to the chipped ice. 105

In testimony whereof I affix my signature.

FREDERICK B. RANNEY.
